UNITED STATES PATENT OFFICE.

CHRISTIAN SEIDEL, OF NEW YORK, N. Y., ASSIGNOR TO J. HENRY PETERS COMPANY, OF SAME PLACE.

DESIGN FOR A SKIRT-BINDING.

SPECIFICATION forming part of Design No. 34,298, dated March 26, 1901.

Application filed February 26, 1901. Serial No. 48,999. Term of patent 7 years.

To all whom it may concern:

Be it known that I, CHRISTIAN SEIDEL, a citizen of the United States, and a resident of the borough of Manhattan, in the city and

5 State of New York, have invented and produced a new and original Design for a Skirt-Binding, of which the following is a specification.

The essential feature of my design consists
10 in a skirt-binding having a brush pendent from one edge thereof, a series of short columns extending along the head in proximity to the brush, and a series of checks so arranged on the head above the series of col-
15 umns as to produce pronounced diagonal lines.

In the accompanying drawing, which rep-

resents a piece of the binding in elevation, the brush is denoted by *a*, the series of short columns in proximity to the brush by *b*, and the diagonal lines of checks by *c*.

What I claim is—

The design for a skirt-binding, substantially as herein shown and described.

In testimony that I claim the foregoing as my invention I have signed my name, in presence of two witnesses, this 20th day of February, 1901.

CHRISTIAN SEIDEL.
